DISPENSER

Maurice J. Blons, Chicago, Ill.

Application April 20, 1943, Serial No. 483,734

2 Claims. (Cl. 312—94)

The invention relates to improvements in dispensers especially adapted for dispensing paper cups and salt tablets for use therein, the primary object of the invention being the provision of an improved arrangement of the character indicated which is of simple construction and highly efficient and convenient in use.

Other objects will appear hereinafter.

The invention consists of the combinations and arrangements of parts hereinafter described and claimed.

The invention will be best understood by reference to the accompanying drawing forming a part of this specification and in which—

Fig. 1 is a top plan view shown partially in horizontal section of a dispenser embodying the invention;

Fig. 2, a partial side view of the same in which the lower portion thereof is shown in vertical section; and

Fig. 3, a partial front view of the same.

The embodiment of the invention illustrated in the drawing comprises a suitable cabinet 10 having a removable cover 11 and provided on one side with a supporting member 12 adapted and arranged to engage with a corresponding supporting bracket for removably supporting the same on a wall or other vertical surface. The casing 10 is divided by a vertical partition 13 into two compartments or magazines 14 and 15. The magazine 14 is open at the bottom but is provided at its bottom with wedge-shaped blocks 16 adapted and arranged to removably support cups 17 in said magazine, with the lower end of the lowermost cup protruding from the bottom of the magazine for ready removal thereof from the magazine, as will be readily understood.

The other magazine 15 is arranged as indicated in front of the cup magazine 14, and has its bottom 18 positioned well above the bottom of the magazine 14 as indicated, said bottom being provided centrally adjacent its outer edge with a discharge opening 19. By this construction a positioning shoulder 20 is provided to the rear of the discharge opening 19 in position to facilitate the arrangement of a cup 17 under said discharge opening to receive a tablet therefrom, as indicated by the dotted lines in Fig. 2.

A discharge wheel 21 is rotatably mounted by means of the screw 22 on the bottom 18 of the magazine 15 with its edge 23 protruding through a slot formed in the front wall of said magazine. The wheel 21 is provided with two diametrically arranged openings or pockets 24 extending therethrough, and so positioned as to be brought into registration with the discharge opening 19 in the bottom 18 when said wheel is revolved. As will be noted, the discharge opening 19 is arranged under the slot in the front wall of the magazine 15 in such position that when one of the open-

ings 24 is brought into registration therewith, it is within the slot in the front wall of the mechanism so as to be effectively covered against the discharge of additional tablets. A sight pocket 5 26 is arranged in the front wall of the magazine 15 and covered by a transparent sheet 27, and whereby one or more tablets 25 may be secured in said opening to indicate the contents of the magazine 15.

In use and in operation the magazine 14 is filled with cups, with the lowermost cup protruding through the open bottom thereof and the magazine 15 supplied with salt tablets 25 or the like. When it is desired to remove a cup and supply the same with a salt tablet, the lowermost cup is drawn downwardly through the open bottom of the magazine 14, the top of the cup yielding inwardly sufficient to permit of this. Then said cup is held centrally under the bottom of the magazine 15 with its rear edge positioned against the shoulder 20, and the wheel 21 manipulated by the thumb or fingers of the operator until one of the tablets is dispensed through the opening 19 into the cup. Owing to the fact that 10 when the openings 24 are brought into registration with the opening 19, the top of the former is covered by the front wall of the magazine 15 and only one tablet can be discharged at a time. By this arrangement the dispensing of the cups 17 with salt tablets 25 therein is greatly facilitated and the handling of the salt tablets absolutely dispensed with.

The specific form and arrangement of parts is a simple and effective one for the purpose.

While I have illustrated and described the preferred form of construction for carrying the invention into effect, this is capable of variation and modification without departing from the spirit of the invention. I therefore do no wish to be limited to the precise details disclosed, but desire to avail myself of such variations and modifications as fall within the scope of the appended claims.

I claim:

45 1. A tablet dispensing magazine having a revolving discharge wheel operating over its bottom, there being a registering slot in a wall of said magazine through which one edge of said wheel projects, said wheel being provided with an opening extended therethrough and movable into and out of said slot, the bottom of the magazine being provided with a discharge opening registering with said wheel opening when in said slot.

50 55 2. A tablet dispenser specified in claim 1 in which means are provided at the bottom of said magazine against which a cup is held for positioning the same to receive a tablet discharged through said bottom opening.
